UNITED STATES PATENT OFFICE

MELVIN O. JENNINGS, OF LEXINGTON, MASSACHUSETTS, ASSIGNOR TO HARRY H. BECKWITH, OF BROOKLINE, MASSACHUSETTS

SHOE HEATER

Application filed August 30, 1929. Serial No. 389,378.

This invention relates to shoe heaters for conditioning a portion of the upper prior to the bed lasting operation. In most of the shoes manufactured, the toe portion of the upper is provided with a stiffening member, both for the purpose of helping to keep the upper in shape and also to protect the toes of the wearer. These stiffening members, known commonly as box toes, may be of various materials. Many box toes are now made of fibrous material mixed with a thermoplastic binder which is stiff when cold but may be rendered flexible by suitable heating. This material is made into sheet form from which blanks of suitable shape are cut. These blanks are warmed to render them flexible and when thus suitably conditioned may be inserted in place with the other materials of the shoe uppers, immediately prior to the pulling-over operation. The pulling-over step bends the upper with the box toe around the toe portion of the last so that the box toe cools and hardens in its ultimate shape. The edges of the box toe which are bent under the last must be heated again prior to the lasting operation in order that these edges may be smoothly secured to the last.

When the uppers are composed of ordinary leather, it is desirable to heat and moisten the toe portion of the upper prior to the bed lasting operation so as to stretch the leather over the toe of the last. There are some delicate leathers, however, which are ruined by moisture so that for these leathers it is desirable that only the turned under marginal portions be heated for the bed-lasting operation, and that very little moisture be used. Dry heat is, in general, objectionable for conditioning box toes, since such heat is liable to "spew" the box toes, that is, to cause the thermoplastic binder to exude. This not only weakens the box toe itself, but is liable to cause the binder to soak into the liner or leather of the upper and spot the leather. Dry heat is also liable to "burn" the leather itself.

According to the present invention a heater is provided which is capable of supplying heat to the under-turned marginal portions of the upper, this heat being accompanied by a small amount of moisture, or, if desired, a

larger amount. According to the invention the shoe heater includes a housing having an upper and a lower portion, the upper portion being removable for replacement by a similar portion or by a heating attachment of another kind for other purposes. This results in an economy in factories where shoes of different types of leather are made in successive batches, some leathers requiring steaming while others require comparatively dry heat.

Various advantageous features of construction will be apparent to one skilled in the art from the disclosure of the invention in the description which follows and on the drawing, of which,

Figure 1 is a perspective view of a shoe heater embodying the invention.

Figure 2 is a section on the line 2-2 of Figure 1.

Figure 3 is a section on the line 3-3 of Figure 2.

The heater illustrated on the drawing comprises a lower casing 10 in which is suitably mounted a receptacle 11 for water to supply whatever moisture may be desired. In order to maintain a relatively small amount of water in the receptacle 11 at a fairly constant level, this receptacle may be connected to a suitable reservoir 12 as by one or more apertures 13. An inverted flask 14 may be employed to supply the reservoir 12. In this way the quantity of water normally in the receptacle 11 is relatively small so that when the apparatus is started up for the day's work, little time is lost in heating the water to operating temperature. The heater also includes an upper casing 15 which fits upon the lower casing 10 and forms therewith a substantially closed housing for the receptacle 11. The top 16 of the housing is preferably sloped, as shown in Figure 2, and is provided with suitable small perforations 17, these perforations being arranged to conform roughly to the contour of the toe portion of a last, as indicated in Figures 1 and 3, so that heated air and moisture passing therethrough will impinge directly on the under-turned margins of the toe portions of the shoe uppers which are tacked to the last.

In order to support the last with its toe

- portion properly positioned over the perforations 17, a fixed rail 18 may be secured to the front of the casing, an adjustable rail 19 being supported by suitable brackets 20.
- 5 An arcuate guide rail 21, also of general horseshoe shape, may be mounted on the top 16 for each set of perforations so as to facilitate the proper positioning of each last. This guide rail preferably extends up slightly 10 above the bottom edge of the last so as to prevent objectionable side drafts due to air currents in the room where the shoe heater is operated, which drafts and air currents would otherwise tend to blow the heat and moisture 15 from the perforations 17 to one side, with the result that the marginal portions of the uppers would be unevenly treated.
- Within the upper casing 15 is supported a 20 heating unit 22 which, as shown, may be encased in a sheath 23 to protect the element within. This heater may be supported as by suitable brackets 24 and is preferably arranged to extend longitudinally from one end of the housing to the other above the receptacle 11. For the purpose of illustration, an electrical heating unit is illustrated. I do not wish to limit myself to this particular form of heater as any equivalent unit such, for example, as a steam pipe may be similarly 25 employed. The unit 22 may be controlled by a suitable switch 25 conveniently mounted at one end of the housing. The function of this unit is not only to heat by contact the air and vapor within the housing, but also to accelerate evaporation of water from the receptacle 11 by the radiant heat projected therethrough downwardly into the receptacle. As the vapor rises from the receptacle 11 and 30 mixes with the air in the casing, it is further heated by contact with the hot unit 22. This results in a supply of heated air containing a relatively small amount of moisture. The flow of air through the perforations 17 may be controlled as by a suitable damper 26 which, as shown in Figure 2, is adjacent to the lip of the receptacle 11 so that when the damper 26 is closed it forms with the receptacle a substantially tight partition below 35 the casing 15.
- If for certain kinds of leather it is desired to supply additional moisture with the heated air, the water in the receptacle 11 may be more strongly heated by heating units 27 40 which may be securely clamped against the bottom of the receptacle 11 as by set screws 28. As shown in Figure 2 two such units are employed, but any convenient number may be employed according to their size and 45 the desired conditions of operation. The heaters 27 may be controlled by a suitable switch 29. These heaters are also convenient when starting up the apparatus for a day's work since by their use the water in the receptacle 11 may quickly be brought up to op-

erating temperature, the bottom heaters being thereafter turned off.

Since the upper heater 22 is mounted in the upper casing 15, it is preferably connected as by a suitable cord 30 and plug 31 70 to the switch box 32. When the plug 31 is pulled out, the casing 15 may readily be removed from the lower casing 10 for replacement by another upper casing of the same or a different type. 75

The housing as a whole may be conveniently supported by a single standard 33 the upper end of which is shown as screw threaded into a casting 34 secured to the bottom of the housing. A suitable base for the standard 33 (not shown) may be secured to the floor. 80

An embodiment of this invention having thus been described, it should be evident to those skilled in the art that various changes 85 and modifications might be made therein without departing from its spirit or scope as defined by the appended claim.

I claim:

A device of the class described comprising 90 a housing having a perforated top, means for supporting a shoe last with its toe portion over said perforations, a guide rail mounted on said perforated top to receive toe portions of lasts, means for heating the air 95 within said housing, means for supplying moisture for the heated air, and means for admitting to the housing a controlled flow of fresh air.

In testimony whereof I have affixed my signature. 100
